(57) **CLAIM**

The ornamental design for an assembly for relay device, as shown and described.

DESCRIPTION

FIG. 1 is a perspective view of an assembly for relay device showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view showing the assembly in a relay device; and,

FIG. 9 is a perspective view showing the assembly in the relay device with a casing.

The broken lines in the drawings depict the casing and the relay device and form no part of the claimed design.
